R. WEIR

DISPLAY STAND

Filed Oct. 2, 1923

FIG. 1.

FIG. 2

INVENTOR.
Robert Weir
BY *Carlos P. Griffin*
ATTORNEY.

UNITED STATES PATENT OFFICE.

ROBERT WEIR, OF SAN FRANCISCO, CALIFORNIA.

DISPLAY STAND.

Application filed October 2, 1923. Serial No. 636,094.

To all whom it may concern:

Be it known that I, ROBERT WEIR, a citizen of the United States, residing at San Francisco, in the county of San Francisco, State 5 of California, have invented a new and useful Display Stand, of which the following is a specification in such full and clear terms as will enable those skilled in the art to construct and use the same.

10 This invention relates to a display stand and its object is to provide a display stand capable of showing cards of various sizes at varying angles, as may be convenient in a window or show case.

15 Another object of the invention is to enable the card holder to be raised or lowered to suit the convenience of other articles in the window.

Another object of the invention is to provide 20 a display stand which is capable of carrying a rack for the display of narrow strips of card, such as, for example are commonly used in restaurants or other places where a strip of card about two inches wide

25 and eighteen or twenty inches long is used to display the name and price of an article, several of them being used, one over the other.

Another object of the invention is to provide 30 means whereby the card holder will frictionally engage the card with sufficient force to prevent it from being easily displaced from the holder.

Other objects of the invention will appear 35 as the description proceeds.

An embodiment of the invention is shown in the accompanying drawings in which the same reference numeral is applied to the same portion throughout, but I am aware 40 that there may be modifications thereof.

Fig. 1 is a front elevation of the holder, Fig. 2 is a side elevation of the holder,

Fig. 3 is a front elevation of the rack used with the holder to display narrow cards,

45 Fig. 4 is an edge view of the rack shown in Fig. 3, and

Fig. 5 is an end view on a larger scale of the card holding bars showing the means for retaining the card in place.

50 The numeral 1 indicates a suitable heavy base which has a rod 2 connected therewith, which rod has a circular head 3 at its upper end, said head forming an eye to receive thumb bolt 4.

55 The thumb bolt passes through two clamps 5 and 6, and is threaded into a nut 7 to en-

able the two clamps to be tightened on the head 3.

The clamps 5 and 6 are shaped to embrace a flat tubular member 8, said member having 60 a bar 9 at its lower end which consists of a piece of sheet metal bent over to form a rounded edge at 10, as shown in Fig. 5, and the metal is also bent up to form a channel to receive the lower edge of a card, as shown 65 at 11.

The extreme edge of the plate is formed as shown at 12 to contact with the back of the plate, the object of this being to exert sufficient frictional pressure upon the lower edge 70 of the card to hold it so that it will not be readily displaced from the holder.

Slidable within the member 8 is another flat tubular member 13 which carries at its top a holder 14 of substantially the same 75 form as the holder 9 except that it is reversed in position so that it will engage the upper edge of the card instead of the lower edge as does the bar 9.

The tubular member 8 is open at the back 80 so that when the clamps are tightened that the outer tubular member will engage the inner tubular member with sufficient force to hold it in a given adjustment.

It will also be seen that the clamps may 85 be tilted to allow the holder to stand at any desired angle with respect to the standard 2, and that the head 3 is sufficiently solid to properly hold the cards in the desired position.

90 The holder shown in Fig. 3, which is used with the stand, consists of two flat members 15 and 16, looped to form a series of hooks 17 and 18 at different elevations along the length of the two bars 15 and 16. These 95 two bars are then connected together by means of two transverse members 19 and 20. In use this frame is inserted in the recessed bars 9 and 14, the same as a card, whereupon narrow strips may then be inserted 100 in the hooks formed in said plate, in such number as may be desirable.

105 What I claim is as follows, but modifications may be made in carrying out the invention shown in the drawings and in the above particularly described form thereof, within the purview of the invention.

110 1. A display stand, comprising a base, a standard carried thereby having an eye at its upper end, a pair of clamps, a bolt passing through said clamps and through the eye of said standard, a tubular member

passing through said clamps, and means at the top and bottom of said tubular member to secure a card in position, the bolt enabling said clamps to be loosened to raise or lower the display and permitting the display to be tilted at will.

2. In a display stand, a base, a standard carried thereby having an eye at its upper end, a pair of clamps, a bolt passing therethrough and through the eye of the standard, a tubular member extending between the clamps, an adjustable bar slidable in said tubular member and means at the top of the adjustable bar and at the bottom of the tubular member for holding a card.

3. In a display stand, a base, a standard carried thereby having an eye at its upper end, a pair of clamps, a bolt passing therethrough and through the eye of the standard, a tubular member passing between the clamps, a plate secured to the lower end of the tubular member one edge of said plate

being formed to produce a receptacle to hold and frictionally engage the lower edge of a card and means slidable in the tubular member to engage and hold the upper edge of a card.

4. In a display stand, a base, a standard carried thereby having an eye at its upper end, a pair of clamps, a bolt passing through said clamps and through the eye of the standard for securing the clamps in any desired angular adjustment, a tubular member slidable in said clamps having a plate at its lower end formed to receive a card holding rack and a card holding rack having a plurality of hooks formed along the same supported by the stand and means at the upper end of the tubular member to engage and hold said rack.

In testimony whereof I have hereunto set my hand this 16th day of September, A. D. 1923.

ROBERT WEIR.
